(57) **CLAIM**

The ornamental design for a food container and the lid for a food container, as shown and described.

DESCRIPTION

FIG. 1 is a top and side perspective view of a food container showing my new design;

FIG. 2 is a view similar to FIG. 1, but with the lid partly removed;

FIG. 3 is a view thereof from the top of FIG. 4;

FIG. 4 is a bottom plan view thereof;

FIG. 5 is a view thereof from the bottom of FIG. 4;

FIG. 6 is a view thereof from the bottom of FIG. 7, the view from the top of FIG. 7 being the mirror image thereof; and, FIG. 7 is a top plan view thereof.
